UNITED STATES PATENT OFFICE

104,403

DESIGN FOR A CASKET BIER OR SIMILAR ARTICLE

William E. Klever, Washington Court House,
Ohio

Application December 10, 1936, Serial No. 66,460

Term of patent 14 years

To all whom it may concern:

Be it known that I, William E. Klever, a citizen of the United States, residing at Washington Court House, in the county of Fayette and State of Ohio, have invented a new, original, and ornamental Design for a Casket Bier or Similar Article, of which the following is a specification, reference being had to the accompanying drawing, forming a part thereof.

Fig. 1 is a perspective view of a casket bier or similar article showing my new design.

Fig. 2 is a top plan view thereof.

The distinguishing and characteristic feature of my design resides in the form and arrangement of the ornamental open-work or scroll decoration as shown, applied to a casket bier of the type and structure disclosed.

I claim:

The ornamental design for a casket bier or similar article, as shown and described.

WILLIAM E. KLEVER.
